KARL P. BILLNER, OF NEW YORK, N. Y.

FLOOR CONSTRUCTION

Application filed May 19, 1930. Serial No. 453,679.

In application for Letters Patent of the United States, filed February 7, 1930, Serial No. 426,519, I disclosed certain improvements in floor construction in which light steel 5 girders or bar joists are employed, running crosswise of the floor and embedded in and supported and reinforced by a filling of porous concrete or so-called aerocrete. My present invention relates to a floor construc- 10 tion of the same general type but embodies improvements by reason of which the construction will be substantially stronger and more rigid for the same weight of materials.

With the arrangement described in my 15 pending application, as well as with all floor constructions in which steel girders or beams have been used, so far as I am aware, the construction has always been what is technically referred to as the single span type. 20 By this is meant that the strength of each span is independent of other spans. For this reason in making calculations based upon assumed loads, the dimensions and sizes of the girders or beams are based upon 25 the load intended to be carried by each span, wholly independent of the other spans.

With my present improvements, I employ 30 a continuous construction through two or more spans, as I will explain, whereby the girders or beams are not independent, and in consequence a very much lighter type of 35 girder or beam can be employed to resist the same load. In a sense the advantage secured in this direction is somewhat cumulative, for the reason that the dead weight of the floor 40 is reduced whereby a saving in steel results from this fact.

In order that the invention may be better 45 understood attention is directed to the accompanying drawing forming a part of this specification and in which

Figure 1 is a cross section of an arrangement of floor construction employing light weight girders or bar joists, and

Figure 2 is a similar view of a floor construction employing transverse I beams.

In both of these views corresponding parts are represented by the same numerals of reference.

With the arrangement shown in Figure 1,

I make use of a series of longitudinal I beams 1, or other form of beam carried in the ordinary way upon posts or pillars (not shown), the beams at the extreme ends being supported by the usual walls of the building as 55 will be understood. The I beams 1 are spaced a proper distance apart, usually not to exceed a maximum of twenty-four feet and extend parallel to each other. Extending crosswise of the I beams and supported by the 60 same are light steel girders or bar joists which can be of any suitable construction, a number of which are referred to in my said application. These are now well known elements in building construction, differing in 65 detail according to different manufacturers or steel fabricators. Their steel characteristic is that they provide great strength with but small weight of steel. These girders are placed generally from twenty to twenty-four 70 inches apart and extend parallel with each other.

The form of girder shown in Figure 1 is merely for the purpose of illustration. It 75 consists of one top flange 2, one bottom flange 3, and interposed members 4 welded or otherwise secured between the top and bottom flanges, so that the whole forms a light lattice girder. As shown, the ends of the bottom flange of each girder are bent up at an 80 angle of ninety degrees more or less, being welded or otherwise secured to the top flange. The girders so formed rest directly upon the upper flange of the I beams 1.

In the arrangement illustrated, I show a 85 pair of plates 5 and 6 which are welded or otherwise secured to the members 2 and 3 and which also rest upon the upper flanges of the I beams. Preferably these plates are somewhat longer than the width of the upper 90 flange of the I beam as shown, so as to strengthen the ends of the girders in such manner that they will be able to withstand the tension occurring at these points under the effect of loads. The plate 5 of one girder, 95 if used, or the members 2 and 3 of that girder, if said plate is not used, are securely tied to the plate 6 of the adjacent girder, if used, or to the members 2 and 3 of that girder if said plate is not used. This tying of the 100

girders together can be effected in any suitable way, but a convenient arrangement is that shown in which a key 7 is employed having enlarged heads engaging correspondingly shaped recesses in the companion plates 5 and 6. When such keys are used to connect the girders together, the channels or recesses for receiving the keys 7 can be formed by machining or otherwise in the separate plates before they are welded to the ends of the girders, thus making the operation an economical one. It will be observed that the heads of the keys 7 not only engage recesses in the plates 5 and 6 but also shallower channels in the flat upper portions of the flanges 3.

By thus rigidly connecting adjacent girders together, it will be seen that any load tending to deform the top flange will be resisted, not only by the flange itself, but also by adjacent girders, thus materially increasing the strength of the structure and permitting lighter girders to be used.

With my improved construction I also equip the upturned vertical end of the bottom flange of each girder with an abutment so as to utilize the bottom flange for compression in the vicinity of the supports or I beams 1, and avoiding any shearing or crushing action at this point. Such an abutment may be a light steel section 8 welded or otherwise secured to the end of the bottom flange of the girder at the point where the bottom flange is bent upwards as shown. The girders are placed in position and a body of concrete 9 is cast or poured around the lower part of each I beam by means of usual forms or molds not shown. The concrete is so cast that it engages the abutment sections 8 which are thereby embedded in the concrete so as to resist compression strains upon the bottom flanges of the girders. Each section 8 is of sufficient area to take the thrust without crushing the concrete in which it is embedded.

After the girders have been placed and tied together they are then completely embedded in a layer 10 of porous concrete or so-called aerocrete through the use of forms or molds of usual construction, not shown. This material, when the molds are removed, forms a smooth and continuous ceiling for the floor below, which if desired, may be coated with any suitable plaster-like material. The coating 10 extends above the girders and constitutes the floor. It may be covered with a suitable surfacing material.

In casting the porous concrete 10, instead of using a bottom form of wood which requires to be removed after the aerocrete has set, I may use a form comprising expanded metal lath of well known construction supported at a short distance below the bottom flanges of the girders. To such a metal lath when used as a form, I may apply a basic

coat of plaster on its underside before the pouring of the expanded concrete, thereby preventing the wet concrete from leaking through the lath. After the expanded concrete has set I may then apply a finishing 70 coat of plaster to the metal lath and thus obtain a finished ceiling without having to remove a wooden form and applying plaster to the undersurface of the expanded concrete.

The arrangement shown in Figure 2 is 75 the same as that just described, except that instead of using light weight girders, I make use of I beams 11, each having a bottom flange 12 and an upper flange 13. Such I beams, if of light weight, may be wholly embedded in a layer of porous concrete as in Figure 1, but when such I beams are of ordinary standard dimensions, it will not be necessary to use the embedding porous cement and therefore, in the latter case, I need use only a relatively thin layer of porous concrete 14 to form the ceiling, and a similar layer 15 to constitute the floor, these layers being poured by the use of ordinary forms.

When an I beam is used instead of a girder 90 as in Figure 1, the plates 5 and 6 are preferably bolted in place as shown. Instead of using an I beam 11 of sufficient strength so as not to require the use of a complete filling of porous concrete as in Figure 1, it will be 95 understood that latticed steel joists may be employed in the same way.

If desired, instead of employing ordinary concrete for covering the I beams 1, any of the light weight concrete may be used, such as cinder concrete, or so-called Haydite concrete, or other concrete in which the aggregate is of a light, porous nature. These materials have sufficient strength for the purpose and have the advantage over ordinary 105 concrete of being relatively light.

By completely embedding light weight 110 girders in a mass of porous concrete or aerocrete a very rigid construction is obtained and any tendency of the girders to buckle under the effect of load strains or of heat in case of fire is prevented. At the same time, the arrangement is fire-proof in a very 115 marked degree, as well as almost entirely sound proof.

In my said application above identified, I refer to the possibility of using relatively large fillers, such as bags containing a light, cheap material, thus reducing the amount of porous concrete necessary in forming the 120 floor, and it will be understood that when the arrangement of Figure 1 is used, these fillers may be employed if desired.

Having now described my invention, what I claim is new therein and desire to secure by 125 Letters Patent is as follows:

1. In a floor construction, the combination of a series of longitudinal supporting members, of transverse members extending 130 across and supported by said members to

form the span, a bottom on each transverse member and a rigid abutment with which the bottom of each transverse member engages to resist the effect of compression strains.

5. 2. In a floor construction, the combination with longitudinal supporting members, of a series of transverse members extending cross-wise between and carried by said longitudinal members to form the span, the transverse members of one span being connected rigidly to the corresponding transverse members of adjacent spans, a bottom on each transverse member and abutments with which the bottom of said transverse members engage to resist compression strains.

10. 3. In a floor construction, the combination with longitudinal supporting members, of a series of light weight girders extending cross-wise between and carried by said longitudinal members to form the span, the girders of one span being connected rigidly to the corresponding girders of adjacent spans, bottom flanges on said girders, abutments with which the bottom flanges of said girders engage and

15. 25 a filling of porous concrete in which all the girders are embedded.

4. 4. In a floor construction the combination of a series of longitudinal members, a body of concrete surrounding each member, abutments embedded in said concrete, light weight cross girders extending between the longitudinal members and supported thereby to form a span, said girders having bottom flanges which engage with said abutments to resist

20. 25 compression strains, and a filling of porous concrete in which said girders are embedded.

5. 5. In a floor construction, the combination with a series of longitudinal members and a body of concrete surrounding each of said members, of a plurality of transverse members extending crosswise and supported thereby to form a span, the transverse members of one span being connected to the corresponding transverse members of an adjacent span, and the transverse members having bottom flanges which are engaged with the adjacent concrete covering the longitudinal members to resist compression strains.

40. 6. 6. In a floor construction, the combination with a series of longitudinal members and a body of concrete surrounding each of said members, of a plurality of light weight girders extending crosswise and supported thereby to form a span, the girders of one span

45. 55 being connected to the corresponding girders of an adjacent span, the compression members of all the girders being in engagement with the adjacent concrete covering the longitudinal members to resist compression

50. 50 strains, and a filling of porous concrete in which all the girders are embedded.

KARL P. BILLNER.
